UNITED STATES PATENT OFFICE

163,554

CASTER SUPPORT OR THE LIKE

Betty Auer, Chicago, Ill.

Application November 5, 1949, Serial No. 5,890

Term of patent 14 years

(Cl. D10—6)

To all whom it may concern:

Be it known that I, Betty Auer, a citizen of the United States, residing at Chicago, in the county of Cook and State of Illinois, have invented a new, original, and ornamental Design for a Caster Support or the Like, of which the following is a specification, reference being had to the accompanying drawings, forming a part thereof.

Fig. 1 is a top plan view of a caster support, showing my new design; and

Fig. 2 is an elevational edge view thereof.

I claim:

The ornamental design for a caster support or the like, as shown.

BETTY AUER.
